UNITED STATES PATENT OFFICE.

RICHARD VARLEY, OF ENGLEWOOD, NEW JERSEY.

ELECTRICAL SYSTEM.

1,112,177.

Specification of Letters Patent. Patented Sept. 29, 1914.

Continuation of application Serial No. 826,236, filed March 21, 1914. This application filed July 1, 1914. Serial No. 848,360.

To all whom it may concern:

Be it known that I, RICHARD VARLEY, a citizen of the United States of America, residing at Englewood, in the county of Bergen and State of New Jersey, have invented new and useful Improvements in Electrical Systems, of which the following is a full, clear, and exact description, reference being had to the accompanying drawings, which form part of this specification.

This invention relates to systems for producing electrical discharges from a source of energy. As such a device I provide means for causing a high tension effectively sustained discharge of current without employment of large and heavy apparatus, and which may find embodiment in many systems, such as wireless telegraphy and ignition systems for exploding the charges of 20 internal combustion engines.

The broad feature, herein disclosed, of building up a supernormal state of flux for prolonged energizing of a current using instrumentality is covered by Patent No. 25 1,081,413, granted to me December 16th, 1913, and to divisional subject matter of which the present application is directed.

In the accompanying drawings hereinafter described I have illustrated my invention 30 as embodied in an ignition system for internal combustion engines but it will be premised that I do not desire to limit myself thereto, said embodiment being only one of the many uses of which my invention is 35 capable.

The usual ignition system employing a coil or generator inductively wound produces a high voltage spark of short duration and low heat, and therefore, poor ignitive value. This is due to the radical magnetizing and demagnetizing effect upon the core or armature of the inductive generator upon breaking of the primary circuit, and resultant non-sustained magnetic flux action; 40 the momentarily induced current in the secondary winding producing a correspondingly short ineffective spark, and while in the alternating current high tension magneto or generator there is a certain amount of current 45 augmentatively, generatively impressed upon the secondary winding of the armature, by reason of its rotation, after the primary cir-

cuit has been interrupted, its amperage is so slight that it is practically impotent. It is also commonly known that in the usual 55 ignition system, self-induction and reactance in the interrupted primary winding, causes flashing or sparking at the interrupted contacts, which necessitates the employment of the more expensive, precious and 60 less readily oxidizable metals, such as platinum and iridium, for contact service, and also requires a condenser or other spark arresting means connected across said contacts, for absorption of such extra or self-induced current, as a protection to the contacts.

By my invention there may be readily formed a spark having the character substantially of arc-sustenance and high heat 70 value as contra-distinguished from the instantaneously delivered low heat spark above referred to, thereby producing a spark operatively alive for a greater period of time relatively to the travel of the piston, 75 than heretofore has been possible and thus making it effective upon thin or weak gas mixtures and such charges as contain occluded dead or weak spots. Furthermore, I provide a system in which I may dispense 80 with the condenser or other spark arresting means.

My invention comprises, broadly stated, the combination with a source of current, of transformer means and mechanism for 85 effecting the energizing of and for so controlling the transformer with respect to the source of current as to cause operative sustained energizing of a current using instrumentality, as prolonged bridging of a spark 90 gap, in the manner to be hereinafter more fully described.

Figure 1 in the accompanying drawings illustrates in diagram my invention as employed in connection with an ignition system, said diagram showing a multipolar or high frequency generator and a battery as the source or sources of energy; Fig. 2 is a diagrammatic view of the transformer element but showing the windings differently disposed, as will be hereinafter more fully described.

While I show a magneto generator of the high frequency type, the same being one of

the many types of inductive or magneto generators for ignition service on automobiles, I do not desire to limit my invention to the employment of any particular type of generator or means affording a source of current, as my device is advantageously operable with different current generating devices or with a battery or accumulator, as the source of energy.

10 The alternating current generator, which is indicated by the numeral 2 in Fig. 1, (preferably being of the standard type for a four cylinder four cycle engine) has its ignition energizing circuit or inductive winding grounded at one end, as at 3, while the other end is adapted to connect through switch mechanism 4 to winding of transformer mechanism 5, forming part of the spark producing apparatus shown. The 15 transformer device comprises a core 6 which may be of any suitable shape or construction and which carries on the legs 7 and 8 thereof windings 9 and 10 respectively both of which are arranged to be grounded, as 20 at 11, through the intermediary of circuit controlling mechanism 12 which may comprise a roller timer of the usual construction, having essentially a revoluble contact arm 13, geared or connected to be driven in 25 synchronism by the engine, and a plurality of symmetrically arranged segmental contacts 14 each of which connects with said windings 9 and 10 of the transformer; it being understood that for a four cylinder 30 four cycle engine, the controller arm 13 will be driven at one-half the speed of the engine to commensurately establish the circuit of the windings for the purpose hereinafter described. Also carried upon the legs 7 35 and 8 of the transformer core 6 are secondary windings *a* and *b* preferably serially arranged, one end connecting with the segments 14 of the controller 12 and the other end connecting with a rotating contact arm 40 45 27 of usual distributor mechanism 28 of the spark producing apparatus, the contacts 29 of which distributor connect with the usual spark plugs 30 of an engine (not shown) that are grounded through the cylinders of 50 the engine, as is understood.

An electrically responsive interrupter or vibrator mechanism 15 is provided for interrupting one or both of the primary windings 8 and 9 of the transformer when the 55 circuit or circuits of said windings are otherwise completed through the controlling mechanism 12. The arrangement is such that the vibrator is connected in active circuit with the windings 9 and 10 of the transformer during utilization of a battery or continuous current, and serves as an interrupter, preferably operatively responsive to the maximum peak or period of flow of the

alternating current, for one of said primary windings (winding 10) when the transformer is connected in the generator circuit. A switch arm 4' of the double-arm switch 4 connects with one end of vibrator winding 16. The opposite end of said winding leads to a vibrator contact 17 and a contact 18 of said switch. Normally in engagement with the vibrator contact 17 is a vibrator blade or armature 19 which is in the circuit of the coil or winding 10 and connects with a switch contact 20. When the double arm switch is shifted to a contact 21 and the contact 18, the vibrator winding is connected to the generator through the switch arm 4'. Movement of the roller timer arm 13 to a segmental contact 14 will 80 complete the generator circuit through the primary windings 9 and 10 of the transformer. That is, current flow from the generator will be through switch arm 4' and vibrator winding, thence in parallel through 85 switch contact 18 and a switch arm 4'' of the switch and transformer winding 9, and through vibrator contact 17 and armature 19 and transformer coil or winding 10 and thence to roller timer ground 11, back to 90 generator through ground 3.

It will be understood that the generator 2 may be driven by the engine through any suitable form of connection or gearing (not shown) so as to energize the coils or windings 9 and 10. The circuits of these windings are closed by the roller timer just prior to the inauguration of the spark. Therefore, energizing of the windings 9 and 10 by the generator induces a magnetic flux in the 100 transformer core 6, which tends to seek the normal magnetic path of the core. The turns of windings of these coils 9 and 10 are unidirectionally wound with the result that the lines of force set up respectively by 105 these two coils meet one another in opposition at an intermediate point in the core, causing them to take an abnormal path. The abnormal path taken is preferably a magnetically reluctant one, as by employing a 110 core, such as shown, in which the flux, upon saturation of the core, takes a leakage path across an air gap or space intermediate the sides of the transformer. As the generator 115 current rises to maximum value, the armature 19 of the vibrator is responsively attracted, through energizing of the winding 15, causing sudden opening of the circuit of the coil or winding 10. As stated above, the point of opening of the circuit may 120 take place at or near the peak or maximum point or period of flow of the current wave. Opening of the circuit of the winding 10 causes a violent change of flux in the leg 8 and the diverted or repressed flux takes the 125 less resistant or normal path provided by

the core, setting up a magnetic surge of great intensity, particularly through the leg 8.

Inasmuch as the circuit of the winding 9 is not broken but remains in energizing relationship with the generator, the rate of change of flux in the leg 7 is not so great as that in the leg 8, upon opening of the circuit of the winding 10, but, with said windings 9 and 10 connected in parallel and the generator operating at normal full load, opening of the circuit of the winding 10 causes a rise in voltage in the winding 9. As a result of said flux change and magnetic surge, the voltage is immediately generatively built up to an intense degree in the secondary coils or windings *a* and *b* of the transformer, breaking down or bridging the air gap between the electrodes or terminals 20 of the spark plug connected, by the distributor, in the circuit of the secondary windings. The spark thus formed is not a mere instantaneous flash or of brief duration, but it continues to burn substantially in the form of a flaming arc maintained by a resident body of flux in the core, for the breaking down of the normal reluctance of the spark gap and inauguration of the spark or arc in effect causes a closing of the circuit containing the 25 secondary coils or windings, with the result that there is established a mutual or reciprocal regulative relationship between the arc and secondary winding or flow of flux which tends to prevent immediate equalization 30 of the flux or demagnetization or dissipation of the energy of the transformer; the arc assuming a rheostatic function and causing the windings *a* and *b* to substantially choke or restrain the large body of flux in 35 such a manner as to prolong its activity with respect to arc or flame maintenance at the plug. Furthermore, the winding 9 continues to supply energy at a slight increase in voltage, to the core 6 and to generatively 40 impress a current, in the particular arrangement shown, upon the secondary coil or winding *a*, assistive or additive to the normal current in the secondary winding set up or induced by the flux in the transformer 45 core.

Instantaneous establishment of the spark at the plug or other current using instrument and its maintained utilization of energy causes the active secondary circuit 50 containing said instrument, to so absorb the energy and control the flux action as to prevent self-inductance of a sparking current in the circuit containing the contacts of the interrupter or vibrator mechanism. As a 55 result, there is little or no tendency to sparking between the said contacts upon opening of the circuit of the winding 10. I am thus enabled to employ ordinary material, such

as copper, for the above parts, and to dispense with the use of a condenser or other 65 spark arresting means which is necessary in the ordinary systems to absorb the sparking resulting from interruption of a primary circuit. However, I do not desire to limit my invention to a system in which no condenser is employed, for a condenser may be necessary in some cases, as where abnormal 70 conditions obtain in the circuits. I have, therefore, indicated such a condenser 22 connected across the contacts of the vibrator 75 mechanism in the usual manner.

When the switch mechanism 4 is shifted to contact 20 and a contact 23, connections are made for energizing the transformer from a source of direct or continuous current, such as a battery, when the generator is not delivering an effective alternating current or when it is desired to run on battery ignition. Shifting of the switch as stated, to position shown in dotted lines, 85 brings the vibrator mechanism 15 into circuit with the coils or windings 9 and 10 of the transformer, and when the roller timer arm 13 connects with a segment 14 the battery current sets up a magnetic flux in the 90 core 6 of the respective transformer, which is trembled or intermittently disturbed by the vibrator mechanism, thus inducing a high potential current in the secondary windings *a* and *b* for energizing of the spark 95 plug or plugs 30; the battery being grounded as at 25, in circuit with ground 11 of the roller timer contact arm 13.

Where my system is employed in connection with a high frequency alternating current generator, such as indicated, the gage or size of the turns of the windings 9 and 10 of the transformer would be preferably such as to present no resistance impeditive to effective flow therethrough of the high frequency current. The result is that such windings would not present a desired resistance to the direct or continuous current of the battery. To overcome any such dissipating action on the battery, incident to said 100 capacity effect of the windings, I may insert a resistance in the battery circuit. Such a resistance is indicated by the numeral 26 and may be of any suitable character, the same being commonly connected to or arranged 115 in series parallel relationship with the transformer windings 9 and 10, when the battery circuit connections, described above, are made and being out of circuit with said windings when the generator connections are 120 made, through the double-arm switch arrangement 4.

I do not desire to limit myself to the particular circuit connections of the vibrator or current actuated interrupter mechanism. 120 It will also be apparent, without necessity

of specific illustration, that other changes 5 may be made in the circuit and switch connections and apparatus shown and described, without departing from the principle of energizing and controlling the transformer. Furthermore, the windings may be variously arranged on the legs of the transformer, as desired. For instance, in Fig. 2 I have shown the secondary windings *a* and *b* as being mounted on the connecting legs 31 and 32 of the transformer core 6 instead of being arranged on the legs 7 and 8 as in the case of the construction shown in Fig. 1, and other arrangements will suggest themselves. Nor do I desire to limit myself to the employment of any particular number of coils or to the placing of said coils on separate or different legs of the transformer. Any suitable form of generator or source of current may be employed without departing from my invention.

The advantages of my invention will be found to reside in a system whereby prolonged energizing of a current using instrumentality, such as a spark plug, is obtained by the use of simple, small and compact mechanism and through the employment of either alternating or continuous current. My system operates to instantaneously break down the resistance of the spark gap with a current of high voltage and to follow the initial discharge with a current of sustained high heat value. In both cases, *i. e.*, either in the use of alternating current or continuous or battery current, this arc-like-spark obtains, said flame being highly effective upon gas charges which cannot be exploded by the usual momentarily delivered spark or flash common to the usual ignition systems heretofore used.

The broad idea of causing a leakage of the flux and restoring the flux to normal, in the production of a current discharge, is not claimed herein, as the same is covered by my above mentioned Letters Patent 1,081,413.

The feature of connecting the windings 50 in parallel with either an alternating current circuit or a continuous current circuit and interrupting alternately one or all of said windings, is not *per se* claimed herein as the same forms subject matter of another 55 application of mine, Serial No. 826,235.

Having thus described my invention, what I claim and desire to secure by Letters Patent is:

1. A source of energy, and a circuit there- 60 for a coil inductively related thereto, current actuated interrupter mechanism in circuit with said coil, and a second coil inductively related to the first coil and having

in circuit therewith a current using instrumentality.

2. A source of energy and a circuit there- 65 for, a coil inductively related thereto, a circuit closing device in circuit with said coil, current responsive means for interrupting the circuit of said coil, and a second coil in- 70 ductively related to the first coil.

3. A source of energy and a circuit there- 75 for, a coil inductively related thereto, means for periodically closing and opening the circuit of said coil, a vibrator in circuit with said coil, and a second coil inductively re- 80 lated to the first coil and having in circuit a current using instrumentality.

4. A source of energy and a circuit there- 85 for, a coil inductively related thereto, means for periodically closing and opening the circuit of said coil, a vibrator in circuit with said coil and said means, and a second coil inductively related to the first coil and hav- 90 ing in circuit a current using instrumentality.

5. A source of current and a coil in circuit therewith, a second coil inductively re- 95 lated to the first coil and having in circuit a current using instrumentality, and means, including an independent circuit and current responsive interrupter mechanism, for building up from said source, energy in said first coil and for transferring said energy to the second coil to energize the current using 95 instrumentality.

6. A source of energy, a secondary coil having a current using instrumentality in circuit therewith, a primary coil, and com- 100 mon means, including a current actuated controlling mechanism, for building up from said source, energy in said primary coil for transferring said energy to said secondary coil to cause an initial high tension discharge at or energizing of said cur- 105 rent using instrumentality and for following the initial discharge by a sustained current discharge.

7. A source of energy, a secondary coil having a current using instrumentality in circuit therewith, a primary coil, and com- 110 mon means, including an independent cir- 115 cuit and current actuated controlling mech- 115 anism for building up from said source energy in said primary coil, for trans- 115 ferring said energy to said secondary coil to cause an initial high tension discharge at or energizing of said current using instrumentality and for following the initial dis- 120 charge by a sustained current.

8. A source of current and a coil in circuit therewith, a second coil inductively re- 120 lated to the first coil and having in circuit a current using instrumentality, and means, including an independent circuit, circuit- 125 closing apparatus and current responsive in-

5. 9. A source of energy, a secondary coil having a current using instrumentality in circuit therewith, a primary coil, and common means, including a circuit controlling device and current actuated interrupter mechanism, for building up from said source energy in said first coil and for transferring said energy to the second coil to energize the current using instrumentality. 65
10. 9. A source of energy, a secondary coil having a current using instrumentality in circuit therewith, a primary coil, and common means, including a circuit controlling device and current actuated interrupter mechanism, for building up from said source energy in said first coil and for transferring said energy to the second coil to cause an initial high tension discharge at or energizing of said current using instrumentality. 70
15. 9. A source of energy, a secondary coil having a current using instrumentality in circuit therewith, a primary coil, and common means, including a circuit controlling device and current actuated interrupter mechanism, for building up from said source energy in said first coil and for transferring said energy to the second coil to cause an initial high tension discharge at or energizing of said current using instrumentality. 75
15. 10. A source of energy, a secondary coil having a current using instrumentality in circuit therewith, a primary coil, and common means, including an independent circuit, circuit controlling apparatus and current actuated interrupter mechanism, for building up from said source energy in said primary coil, for transferring said energy to said secondary coil to cause an initial high tension discharge at or energizing of said current using instrumentality and for following the initial discharge by a sustained current discharge. 80
20. 10. A source of energy, a secondary coil having a current using instrumentality, a primary coil, and common means, including an independent circuit, circuit controlling apparatus and current actuated interrupter mechanism, for building up from said source energy in said primary coil, for transferring said energy to said secondary coil to cause an initial high tension discharge at or energizing of said current using instrumentality and for following the initial discharge by a sustained current discharge. 85
25. 11. A source of energy and a coil connected thereto, a plurality of coils, related to said first coil, and means, comprising a core and vibrator mechanism, for building up from said source energy in one of said coils and for transferring said energy to another of said coils and at the same time supplying energy from said source. 90
30. 11. A source of energy and a coil connected thereto, a plurality of coils, related to said first coil, and means, comprising a core and vibrator mechanism, for building up from said source energy in one of said coils and for transferring said energy to another of said coils and at the same time supplying energy from said source. 95
35. 12. A source of electrical energy and a plurality of coils inductively related to one another, secondary winding subject to inductive influence of said coils and having in circuit a current using instrumentality, and means, including current actuated make and break mechanism for building up from said source energy in said coils and for transferring said energy to the secondary winding to energize the current using instrumentality. 100
40. 12. A source of electrical energy and a plurality of coils inductively related to one another, secondary winding subject to inductive influence of said coils and having in circuit a current using instrumentality, and means, including current actuated make and break mechanism for building up from said source energy in said coils and for transferring said energy to the secondary winding to energize the current using instrumentality. 105
45. 13. A source of electrical energy and a plurality of coils, secondary winding subject to inductive influence of said coils and having in circuit a current using instrumentality, and means, including vibrator mechanism, for building up from said source energy in the said coil and for transferring said energy to the secondary winding to cause an initial high tension discharge at or energizing of the current using instrumentality and for following said initial discharge with a sustained flow of current. 110
55. 13. A source of electrical energy and a plurality of coils, secondary winding subject to inductive influence of said coils and having in circuit a current using instrumentality, and means, including vibrator mechanism, for building up from said source energy in the said coil and for transferring said energy to the secondary winding to cause an initial high tension discharge at or energizing of the current using instrumentality and for following said initial discharge with a sustained flow of current. 115
60. 14. A transformer provided with a plurality of windings, one of which is for connection with a source of electrical energy, a
5. circuit comprising a second one of said windings, and means for intermittently closing and opening the circuit of a third one of said windings and comprising current actuated make and break mechanism. 65
15. 15. A transformer provided with a plurality of windings, one of which is for connection with a source of electrical energy, a circuit comprising a second one of said windings, and means for intermittently closing and opening the circuit of a third one of said windings and comprising circuit closing apparatus and interrupter mechanism. 70
16. 15. A transformer provided with a plurality of windings, one of which is for connection with a source of electrical energy, a circuit comprising a second one of said windings, and means for intermittently closing and opening the circuit of a third one of said windings and comprising circuit closing apparatus and current responsive interrupter mechanism. 75
17. 16. A transformer provided with a plurality of windings, one of which is for connection with a source of electrical energy, a circuit comprising a second one of said windings, and means for intermittently closing and opening the circuit of a third one of said windings and comprising vibrator mechanism. 80
18. 17. A transformer provided with a plurality of windings, one of which is for connection with a source of electrical energy, a circuit comprising a second one of said windings, and means for intermittently closing and opening the circuit of the first one and a third one of said windings and comprising circuit closing apparatus and interrupter mechanism. 85
19. 18. A transformer provided with a plurality of windings, one of which is for connection with a source of electrical energy, a circuit comprising a second one of said windings, and means for intermittently closing and opening the circuit of the first one and a third one of said windings and comprising circuit closing apparatus and current responsive interrupter mechanism. 90
20. 19. A plurality of windings, circuit controlling means for connecting said windings with a source of energy, secondary winding inductively related to said windings and second controlling means for said plurality of windings. 115
21. 20. A plurality of windings, circuit controlling means for connecting said windings with a source of energy, secondary winding inductively related to said other winding, and current responsive interrupter mechanism for the circuits of said plurality of windings. 120
22. 21. A source of energy, a plurality of pri-

- mary windings inductively related to one another and connected in parallel with said source, secondary winding inductively related to said primary windings, and current responsive interrupter mechanism in circuit with one of said primary windings.
23. A source of energy, a plurality of primary windings inductively related to one another and connected in parallel with said source, secondary winding inductively related to said primary windings, and current responsive interrupter mechanism in circuit with said primary windings.
24. A source of energy, a plurality of primary windings inductively related to one another and connected in parallel with said source, a plurality of secondary windings, and current responsive interrupter mechanism in circuit with said primary windings.
25. A source of energy, a plurality of primary windings, means for causing current to intermittently flow in parallel through said windings from said source, secondary winding inductively related to said primary windings, and make and break mechanism in circuit with one of said primary windings and said means.
26. A source of energy, a plurality of primary windings, means for causing current to intermittently flow in parallel through said windings from said source, secondary winding inductively related to said primary windings, and vibrator mechanism in circuit with one of said primary windings and said means.
27. A source of energy, a plurality of primary windings, means for causing current to flow in parallel through said windings from said source, secondary winding inductively related to said primary windings, and vibrator mechanism in circuit with said primary windings and said means.
28. A source of energy, a plurality of primary windings inductively related to one another, secondary winding inductively related to said primary windings, means for bringing said primary windings in circuit with said source and comprising make and break mechanism, and a current responsive interrupter device for disconnecting the windings from said source.
29. A source of energy, a transformer core, a plurality of coils adapted for connection with said source and so arranged with respect to the core as to set up in the latter opposing lines of magnetic flux, secondary winding inductively related to one of said coils, and current responsive make and break mechanism in circuit with one of said coils and said source.
30. A source of energy, a transformer core, a plurality of coils adapted for connection with said source and so arranged with re-

spect to the core as to set up in the latter opposing lines of magnetic flux, secondary winding inductively related to one of said coils, circuit closing means for bringing one of said coils intermittently into circuit with said source, and interrupter mechanism for bringing said coil out of circuit with said source.

31. A source of energy, a transformer core, a plurality of coils adapted for connection with said source and so arranged on the core as to set up a magnetic flux therein, secondary winding inductively related to one of said coils, means for connecting said coils with the source of energy to set up a magnetic flux having opposing lines of force, and current responsive interrupter mechanism for bringing one of said coils out of circuit with said source.

32. A source of energy, a transformer core, a plurality of coils adapted for connection with said source and so arranged with respect to the core as to set up in the latter opposing lines of magnetic flux, secondary winding inductively related to said core, circuit connections for bringing said coils into circuit with the source of energy, and current responsive make and break mechanism in circuit with said coils.

33. A transformer core, means for setting up therein a magnetic flux and causing said flux to take a leakage path and comprising a plurality of windings adapted for connection with a source of energy, secondary winding inductively related to said core, and current responsive interrupter mechanism in the circuit of one of said first named windings.

34. A transformer core having a closed magnetic circuit, a plurality of primary windings on said core and adapted for connection with a source of energy, secondary winding inductively related to one of said primary windings, and current actuatable interrupter mechanism in circuit with one of said primary windings.

35. A transformer core having a closed magnetic circuit, a plurality of primary windings on said core, means for connecting said windings in parallel with a source of energy, secondary winding inductively related to said primary windings, and vibrator mechanism associated with said primary windings.

36. A plurality of windings, secondary winding inductively related thereto, a source of current, means for intermittently bringing one of said plurality of windings into circuit with said source, and current responsive controlling means in circuit with another of said plurality of windings and said source.

37. A plurality of windings, secondary

- winding inductively related thereto, a source of current, interrupter mechanism having winding, means for bringing one of said plurality of windings into circuit with said 5 interrupter and another of said plurality of windings into circuit with winding of said interrupter mechanism.
38. A plurality of windings, secondary winding inductively related thereto, a source 10 of current, current responsive interrupter mechanism having winding in energizing circuit with said source and one of said plurality of windings, and means for bringing said interrupter into circuit with another of said plurality of windings 15
39. A plurality of primary windings, current responsive make and break mechanism, means for connecting all of said windings to a source of alternating current and one of 20 said windings in circuit with said make and break mechanism and for bringing said windings out of alternating current circuit and into circuit with a source of continuous current and with said make and break mechanism. 25
40. A source of alternating current, primary winding, secondary winding inductively related thereto, and current actuable make and break mechanism in circuit with 30 a portion of said primary winding and having winding in shunt with said source of current. 35
41. A source of alternating current, primary winding, secondary winding inductively related thereto, current actuable make and break mechanism in circuit with a por-
- tion of said primary winding and having energizing winding, and means for intermittently bringing said energizing winding into circuit with said source and another portion 40 of said primary winding.
42. A source of alternating current, a source of continuous current, primary winding, secondary winding inductively related thereto, interrupter mechanism having energizing winding and means for intermittently connecting said energizing winding in circuit with a portion of said primary winding and the source of alternating current and for connecting said vibrator energizing winding in connection with all of 45 said primary winding and the source of continuous current. 50
43. A transformer core, a plurality of coils arranged thereon, secondary winding 55 inductively related thereto, current responsive make and break mechanism, and means for connecting all of said coils in parallel with a source of alternating current and one of said coils in circuit with the make and break mechanism and for bringing said windings out of alternating current connection and into energizing relationship with a source of continuous current and into circuit 60 with said make and break mechanism. 65

In testimony whereof I have hereunto set my hand.

RICHARD VARLEY.
